(57) **CLAIM**

The ornamental design for a shelf board, as shown and described.

DESCRIPTION

FIG. 1 is right side view of a shelf board showing my new design in accordance with a first embodiment of the present invention;

FIG. 2 is a left side view thereof;

FIG. 3 is a rear view thereof;

FIG. 4 is a front view thereof;

FIG. 5 is a top plan view thereof;

FIG. 6 is a bottom view thereof;

FIG. 7 is a front, right side, top plan perspective view thereof;

FIG. 8 is a reference view thereof showing state in use;

FIG. 9 is a reference view thereof showing state in use;

FIG. 10 is a reference view thereof showing state in use; and,

FIG. 11 is a reference view thereof showing state in use.

The broken lines in the drawings are for the purpose of illustrating environment and form no part of the claimed design.

1 Claim, 11 Drawing Sheets
